[57] ABSTRACT

Apparatus for cleaning floor surfaces having spots or patches of grease, oil or like waste, including supplies of water, soap and detergents fed through a mixing chamber to a brush member. Instead of a brush member, a wax applicator or a sponge device may be connected to the mixing chamber.

HYDRO-BROOM

BACKGROUND OF THE INVENTION

Apparatus for cleaning floors of simple and complex design have long been known, one of the simple devices being a broomlike structure having bristles formed of flexible material. Such broom structure, however, is not an adequate tool in cases, for instance garages wherein the floors may have spots of grease, oil or other industrial waste materials. Similar problems occur in workshops, service stations and the like. It is obvious that any attempt to clean such floors with a dry brush member will not provide the solution. In order to remove grease, oil and the like from the floor, it is necessary to use soap or detergents and also, in some instances, water supply preferably under pressure.

The present invention provides a simple and inexpensive cleaning tool which combines a brush member having bristles with dispensing means for detergents and water supply facilities.

Another embodiment of the invention provides a waxing member to be used after the floor has been cleaned.

A further embodiment comprises a sponge device to be used in particular for inside floors.

SUMMARY OF THE INVENTION

Cleaning apparatus for large residential or industrial floor areas soiled by patches of oil, grease and the like, the apparatus combining water supply under pressure with detergents fed to a brush through a mixing chamber. Control members are provided for regulating the flow of the water and detergents. A waxing device and a sponge element may be substituted for the brush.

BRIEF DESCRIPTION OF THE DRAWINGS

FIG. 1 is a perspective view of an embodiment of the invention;

FIG. 2 is an enlarged view partly in section along line 2-2 of FIG. 1;

FIG. 3 is a plan view, partially in section, of the embodiment of FIG. 2;

FIG. 4 is an enlarged sectional view along line 4-4 of FIG. 2;

FIG. 5 is an enlarged elevational view of the embodiment of FIG. 1, with parts shown in section;

FIG. 6 is an enlarged fragmentary view of the reverse side of the embodiment of FIG. 5;

FIG. 7 is a plan view of a mixing chamber;

FIG. 8 is a sectional view along line 8-8 of FIG. 7;

FIG. 9 is a top plan view of the brush member;

FIG. 10 is a side elevational view of the brush member of FIG. 9;

FIG. 11 is a plan view of a waxing applicator;

FIG. 12 is a sectional view of the waxing applicator along a line 12-12 of FIG. 11;

FIG. 13 is a plan view of a sponge-mop device;

FIG. 14 is a sectional view of the sponge device along a line 14-14 of FIG. 13;

FIG. 15 is a bottom plan view of the waxing applicator fitted with a support plate, and

FIG. 16 is a median sectional view of the waxing applicator of FIG. 15.

2
DESCRIPTION OF THE PREFERRED EMBODIMENTS

Referring to FIGS. 1, 5, 6, the hydro-broom generally designated by reference character 10 includes a brush member 12 mounted in a mixing chamber 14 to which is attached the lower end of a tube 16 comprising a water supply line. A box 18 containing a detergent is mounted on top of the mixing chamber 14 in a manner which will be described in detail hereinafter. The upper end of the tube 16 is fastened to a handle member 20. The handle member 20 is provided with a fitting 22 which enables connecting the tube 16 with a garden hose 24 which in turn is connected to a source of water (not shown). A valve 26 of conventional design mounted to the handle member 20 is provided with a lever 29 for controlling the quantity of water to be fed to the hydro-broom.

20 A valve member 30 disposed in the detergent box 18 is provided for controlling the amount of detergent to be dispensed into the mixing chamber 14. The valve member 30 is controlled by means of a flexible line 32 extending from the valve member 30 along the tube 16 to a control lever 34 which is pivotally mounted to the handle member 20, details thereof being described hereinafter.

25 FIGS. 2 to 5 and 7 to 10 illustrate details of the mixing chamber 14, the brush member 12 and the detergent box 18 mounted on the mixing chamber. Bristles 36 are fastened in a conventional manner to a bristle carrier plate 38 of generally rectangular shape, both being formed of plastic material. A fitting 40 is molded integrally with the mixing chamber 14, the axis of the fitting 40 having an angle alpha with the base plane of the mixing chamber, as indicated in FIG. 8 of approximately 45° to 60°. The fitting 40 is threaded and adapted to receive the lower end of the tube 16 which is similarly threaded. The fitting may also be provided 30 with a twist lock in a conventional manner.

35 FIG. 4 illustrates the way in which the detergent box 18 is releasably fastened to the mixing chamber 14. On the top surface of the mixing chamber 14, a number of cylindrical protrusions 42 are molded integrally with the top plate of the mixing chamber. The protrusions 42 are formed such as to have top circular flanges 44, the diameter thereof being somewhat larger than the diameter of the protrusions.

40 The detergent box 18 is provided on its base 46 with the same number of protrusions 48 which are also molded integrally with the base 46. The protrusions 48 are formed such as to have each an annular groove 50 having a diameter slightly smaller than the diameter of the top flange 44 of protrusion 42.

45 In mounting the detergent box 18 onto the mixing chamber 14 the protrusions 48 of the detergent box are positioned accurately over the protrusions 42 of the mixing chamber and subsequently a slight pressure is applied in pushing down the detergent box such that the flanges 44 snap into the grooves 50. The attachment of the detergent box with the mixing chamber is thus secured.

50 The bristle carrier plate 38 is provided with a relative great number of through-going holes 52 arranged in horizontal and vertical lines as best shown in FIG. 9. The holes 52 are positioned such as to be staggered relative to and not interfere with the bristles.

The mixing chamber as seen in FIGS. 1, 5 and 7, 8 is of a shell-type configuration having a rectangular base. The chamber is provided with two reinforcing ribs 54 as shown in FIGS. 7 and 8. Four stop members 56 molded integrally with the shell body of the mixing chamber for the purpose of securely positioning the bristle carrier plate 38 within the mixing chamber.

An elongate flange portion 58 is integrally molded with the shell body 14 such as to extend along a greater part of the longitudinal side 60 of the shell body. The flange portion 58 serves to keep the bristle carrier plate in position within the mixing chamber, as will next be explained.

As best seen in FIG. 10, the bristle carrier plate 38 is of generally rectangular cross section, but the lower side 62 — as shown in the drawing — of the rectangle is, unlike the other three sides, not straight but of a slightly curved configuration.

In assembling the apparatus the bristle carrier plate 38 is introduced into the mixing chamber 14 by first moving the upper side 64 of the plate 38 slantingly into the chamber 14 to the upper stops 56 and behind the flange 58, and subsequently pivoting the plate 38 around the side 64 which rests on the upper stop members 56, until the lower side 62 of the plate 38 comes to rest on the lower stop members 56. Since the lower side 62 is, as previously stated, of curved configuration the pivoting movement of the plate 38 is performed smoothly and without encountering any obstruction.

Once the plate 38 is in position, resting on the stop members 56 and the upper part covered by the flange 58, screws 66 on the outside of the shell 14 which may be of the wood screw type, preferably having wing heads enable fastening the plate 38 to the shell side, thus securing a stable and rigid position of the bristle plate in the mixing chamber.

FIG. 5 illustrates the detergent box 18 and the valve lever 28 mounted thereon or regulating the quantity of detergent to be fed to the mixing chamber 14. As previously indicated, a flexible line 32 fastened to the control lever 34 which is pivotably mounted on the handle member 20 preferably is conducted through eyelets 68, 69 on fittings 70 and 72 on the tube 16, through an eyelet 71 in the valve lever 28 to a knob 73 on valve lever 28 and fastened as a loop around it. The valve lever 28 is positioned over the detergent box 18 such as to be pivotable about a lower edge 75 of the lever. The valve 30 comprises a rod 78 carried by the lower portion 76 of the lever 28 which rod is surrounded by a spring 80. The lower end of rod 78 is fastened to the valve body 82 which is disposed over valve seat 84.

When the operator wishes to release a quantity of detergent into the mixing chamber 14 he presses control lever 34 down. The pivoting movement of lever 34 causes line 32 to be pulled whereby the valve lever 28 exercises a pivoting motion around edge 75 to the right — as seen in FIG. 5 of the drawing. This last pivoting motion of lever 28 causes the fitting of rod 78 against the force of spring 80 and the separating of the valve body 82 from valve seat 84, thereby opening the valve and permitting detergent to flow from the box 18 through the orifice 86 into the mixing chamber 14. By pressing the lever 34 more or less the operator is able to control the quantity of detergent to be released into the mixing chamber.

FIGS. 11, 12 and 15, 16 illustrate another embodiment of the invention. Here, the mixing chamber 14

does not contain the brush plate 38 with its bristles 36, but instead a wax applicator 87 joined to a support plate 88 is placed in the mixing chamber. The support plate 88 has a small rectangular recess 90 on its upper side 92 — as seen in FIG. 16 of the drawing — which recess aids in introducing the wax applicator behind the flange 58.

The wax applicator comprises a rectangular base plate 94 formed of wood or plastic material and a fabric 96 of cloth suitable for waxing which is either cemented to the base plate 94 or wrapped around it and glued thereto. On the lower side of the support plate 88 — on the left side in FIG. 16 of the drawing — a small bushing 98 is secured thereto. The wax contained in the box 18 flows from there through a hole 100 in the bushing 98 and bores 102 which are arranged on the center line of the base plate 94 to the fabric 96. Two threaded bolts 104 traverse the base plate 94 and the support plate 88, and together with wing nuts 103 serve to secure the two plates to one another.

A further embodiment of the invention is illustrated in FIGS. 13 and 14. The support plate 94 as previously described with regard to FIGS. 12 and 16 is here in FIG. 14 shown connected to a sponge mopping member 106. The connection is obtained by gluing in a conventional manner. A plurality of holes 107 in the support plate 94 are arranged along lines as shown in FIG. 13. The holes may be arranged in a different order. A lever plate 108 having a handle 109 is constructed to be pivotable around an axis vertical to the drawing plane and adjacent the lower end of the support plate 94 such that when the lever plate 108 is pivoted into the upper position, as shown in the drawing, the sponge mopping member 106 is squeezed and any liquid containing waste substances is removed from the sponge mopping member.

What it is desired to secure by Letters Patent of the United States is claimed:

1. Apparatus for cleaning large floor areas covered with spots of oil, grease and the like, said apparatus comprising in combination

- A. a trough shaped mixing chamber having an open bottom in which water and a chemical substance supplied thereto may be mixed;
- B. a box for receiving and holding a chemical substance, said box disposed above the mixing chamber and in communication therewith;
- C. valve means normally blocking flow from said box to said chamber;
- D. elongated conduit means for feeding water into the mixing chamber from a supply;
- E. handle means connected to the conduit means;
- F. means attached to the handle means for controlling the quantity of water fed into the mixing chamber;
- G. actuating means associated with the handle means for opening said valve means to regulate the amount of the chemical substance fed into the mixing chamber;
- H. means for treating the surface of the floor area, said last means being secured within the mixing chamber and closing the bottom thereof;
- I. and a plurality of stop members integrally formed within said trough and a longitudinal flange integral with the bottom edge of the chamber and extending along a relatively great portion thereof;

J. said means for treating the floor area comprising a carrier plate of generally rectangular configuration having a floor treating element attached thereto, a plurality of holes extending through the carrier plate to allow passage of liquid from the mixing chamber to the floor treating element, the carrier plate having at least one curved longitudinal side which facilitates positioning the second longitudinal side of the carrier plate intermediate the longitudinal flange of the mixing chamber and the stop members.

2. Apparatus as claimed in claim 1 in which the means for controlling the quantity of water includes a valve and a control lever associated therewith readily operable when holding the handle.

3. Apparatus as claimed in claim 1, wherein said floor treating element comprises a plurality of brush bristle groups attached to the carrier plate, the holes in the carrier plate being staggered relative to the attachment points of the bristle groups.

4. Apparatus as claimed in claim 1, wherein said floor treating element comprises a sponge mopping member.

5. Apparatus as claimed in claim 1, wherein said floor treating element comprises a wax applicator fabric.

6. Apparatus as claimed in claim 1 in which the actuating means comprises, a control lever pivotally fastened to the handle means and a flexible line extending

from the control lever along the conduit means to the valve means, wherein, upon pivoting the control lever the flexible line is pulled up, causing opening of said valve means to admit the chemical substance into the mixing chamber.

7. Apparatus as claimed in claim 6 in which the valve means include

- A. a valve lever mounted over the box and having an edge on the bottom thereof about which the valve lever is pivotable,
- B. a valve rod secured to the lower portion of the valve lever,
- C. a valve body fastened to the lower end of the valve rod,
- D. a helical spring mounted over the valve body so as to surround the valve rod,
- E. a valve seat secured to the base of the box and adapted to receive the valve body for closing the valve.

20 8. Apparatus as claimed in claim 7 in which the top portion of the valve lever comprises an eyelet, and

25 knob means below the eyelet, the flexible line being adapted to traverse the eyelet and be secured to the knob means, whereby upon the flexible line being pulled, the valve lever is pivoted about the pivoting edge causing the opening of the valve.
